UNITED STATES PATENT OFFICE.

MARCUS E. BENSON, OF WEST PLAINS, MISSOURI.

SAW-MILL DOG.

SPECIFICATION forming part of Letters Patent No. 436,203, dated September 9, 1890.

Application filed March 24, 1890. Serial No. 345,020. (No model.)

To all whom it may concern:

Be it known that I, MARCUS E. BENSON, of West Plains, in the county of Howell and State of Missouri, have invented a new and 5 Improved Saw-Mill Dog, of which the following is a full, clear, and exact description.

The object of the invention is to provide a new and improved saw-mill dog which is simple and durable in construction, very effective 10 in operation, and permits of freely moving the log up or down in case of knots or crooks striking the collar of the saw, without, however, releasing the dog.

The invention consists of certain parts and 15 details and combinations of the same, as will be hereinafter more fully described, and then pointed out in the claims.

Reference is to be had to the accompanying drawings, forming a part of this specification, 20 in which similar letters of reference indicate corresponding parts in all the figures.

Figure 1 is a side elevation of the improvement with parts in section. Fig. 2 is an enlarged sectional side elevation of part of the 25 improvement, and Fig. 3 is an enlarged sectional plan view of the same on the line $x-x$ of Fig. 1.

On the head-block A of the saw-mill is secured a standard B, on which is held an adjustable frame C, having near its upper and lower ends a slot C', through which pass bolts D, screwing into the standards B and permitting a horizontal adjustment of the 30 said frame C. When the latter is in its innermost position, as shown in Fig. 3, its inner planed edge C² fits into a vertical guideway B', formed on the standard B and serving to limit the inward motion of the frame C. The bolts D are then in the right-hand end of the 35 slots C', as is plainly shown in Fig. 1.

In order to conveniently move the frame C horizontally on the bolts D in order to adjust the dogs farther in or nearer to the side of the log, levers E and E' are provided, pivoted at E² or E³, respectively, to the standard B and preferably made of L shape, one end of each being pivoted to the frame C, while the other ends of the two levers are pivotally connected with each other by the link E⁴, so 45 that when one lever is moved the other moves simultaneously, and the frame C is regularly 50

adjusted forward or backward—that is, nearer to or farther from the log under treatment.

The lever E is provided with a handle E⁵ for conveniently actuating the two levers 55 simultaneously to move the frame C. The latter is provided with a forwardly-extending projection or flange C³, on the front edge of which is arranged a guideway C⁴, and a similar guideway C⁵ is formed on the right-hand 60 side of the frame C, as is plainly shown in Fig. 3, the two guideways C⁴ and C⁵ being engaged by a vertical sliding carriage F, carrying the upper dog G, provided with the usual point G', adapted to engage the log 65 under treatment.

On the upper part of the carriage F is mounted to turn in suitable bearings the transversely-extending shaft H, on which is secured a gear-wheel I, in mesh with a rack 70 J, fitted to slide vertically on the inner face of the projection C³.

The rack J is supported at its lower end on a vertically-extending coiled spring K, extending through a recess C⁶, formed in the projection C³, the upper end of the spring being fastened to the top of the frame C. (See Fig. 1.) On the lower end of the rack J is secured a slide or carriage L, fitted to slide on the guideways C⁴ and C⁵, similarly to the carriage 75 F, the said slide L supporting the lower dog N, provided with the usual upwardly-extending point N', adapted to engage the log from the under side, as is plainly shown in Fig. 1.

The gear-wheel I, previously mentioned, is 85 adapted to be engaged by a pawl O held on two bolts P, extending transversely through slots Q' in the lever Q, fulcrumed loosely on the shaft H on which the lever Q is fulcrumed. The bolts P also support on the opposite face of the lever Q an arm R, having a segmental edge R', adapted to be pressed in contact by a spring R² with the segmental edge F', formed on the carriage F, concentric with the shaft H on which the lever Q is fulcrumed. The said arm R is also adapted to be engaged 90 by the beveled end of a plate F², secured to the top of the carriage F and having its point passing onto the segmental edge F' of the carriage F, as is plainly shown in Fig. 2.

When the lever Q is thrown into a vertical 100 position, the arm R travels up the beveled end of the plate F², so that the said arm

slides outward and carries along the pawl O, which latter is thus disengaged from the gear-wheel I.

When the lever Q is moved downward, so 5 that the arm R passes off the beveled end of the plate F², then the spring R², pressing on the said arm R, causes the latter to slide inward, thereby moving the pawl O in the same direction—that is, in engagement with two 10 teeth of the gear-wheel I.

On the shaft H and at its front end is fulcrumed loosely a cam S, supported on an arm S', fastened to the lever Q, so that the said cam S turns with the swinging of the lever 15 Q, as hereinafter more fully described.

The cam S is adapted to engage with its cam-edge the releasing-arm T, pivoted at T' to the dog G, and adapted to engage with its outer end T² the log under treatment next to 20 the point G', so as to withdraw the latter whenever desired, and as hereinafter more fully described.

The operation is as follows: The operator first moves the lever Q into a vertical position, so as to disengage the pawl O from the gear-wheel I, as previously described, to enable the operator to move the carriage F into the uppermost position, the gear-wheel I then traveling loosely over the rack J. The operator 25 then throws the lever Q into a horizontal position, so that the pawl O engages the gear-wheel I, as previously described, and as the entire weight of the said carriage and its contents now hangs on the rack J, the latter 30 slides downward until the lower dog N is below the top of the head-block A, thereby permitting the log to be rolled onto the head-block in the usual manner until it rests against the outside of the projection C³. When 35 the log has been rolled on the head-block, the operator raises the lever Q into a perpendicular position, so as to disengage the pawl O from the gear-wheel I, thereby releasing the rack J from the weight of the carriage F, so 40 that the said rack slides upward by the action of the spring K and moves the lower dog N, with its point N', into the log from underneath. At the same time the operator lets the carriage F slide downward by its own 45 weight, so that the point G' of the upper dog G engages the log from the top. The operator then swings the lever Q downward into about the position shown in Fig. 1, so that the gear-wheel I is turned in the direction of 50 the arrow a', thereby exerting the upward pressure against the rack J, at the same time causing the downward sliding of the carriage F, whereby the points G' and N' of both dogs G and N are moved toward each other and 55 pressed into the log, so that the latter is securely held in place.

It will be seen that as the lower dog N is supported on the rack which supports the carriage carrying the upper dog and is yieldingly mounted on the spring K, it follows that 60 in case the saw strikes knots or crooks the

log can yield, at the same time being securely held in place by the two dogs.

It will further be seen that when the operator desires to release the points G' and N' 70 of the dogs G and N from the log, the operator moves the lever Q upward, so that the gear-wheel I travels in the inverse direction of the arrow a' and moves the rack J downward and the carriage F upward, thereby 75 withdrawing the points of the two dogs from the log.

When the operator desires to grasp the cant or squared log to be sawed up to the last board, he moves the handle E⁵ of the lever E down, so that the frame C slides to the right until the points of the dogs G and N project only three-quarters of an inch into the timber. The operation of dogging the cant is 80 then the same as for the log.

When the lever Q is moved upward to disengage the points G' and N' of the two dogs G and N from the log, the cam S presses on the releasing-arm T, so that the end T² of the latter engages the rim of the log alongside 90 the point G', so that the latter is easily withdrawn.

Having thus fully described my invention, I claim as new and desire to secure by Letters Patent—

1. The combination, with the frame, of a vertically-reciprocating rack-bar thereon carrying the lower dog and having a free upward movement beyond that required to bring the said lower dog into engagement with the log, with a carriage mounted on the frame and having a gear engaging the rack to raise and lower it, and means for locking the gear to the rack, whereby if an obstruction on a dogged log strikes the saw-collar and causes 105 the log to rise, the rack with the two dogs will yield upwardly, substantially as set forth.

2. In a saw-mill dog, the combination, with a frame and a vertically-sliding spring-supported rack supporting the lower saw-mill dog, of a gear-wheel in mesh with the said rack and a carriage mounted on the frame and carrying said gear-wheel and supporting the uppermost dog, substantially as shown and described.

3. In a saw-mill dog, the combination, with a frame and a vertically-sliding spring-supported rack supporting the lower saw-mill dog, of a gear-wheel in mesh with the said rack, a carriage mounted on the frame and carrying said gear-wheel and supporting the upper dog, and a pawl and lever for turning the said gear-wheel, substantially as shown and described.

4. In a saw-mill dog, the combination, with a frame and a vertically-sliding spring-supported rack supporting the lower saw-mill dog, of a gear-wheel in mesh with the said rack, a carriage mounted on the frame and carrying said gear-wheel and supporting the upper dog, a pawl and lever for turning the said gear-wheel, and means, substantially as

described, for disengaging the said pawl from the said gear-wheel, substantially as shown and described.

5. In a saw-mill dog, the combination, with a yieldingly-mounted rack supporting the lower saw-mill dog, of a gear-wheel in mesh with the said rack, a carriage carrying said gear-wheel and supporting the upper dog, a pawl and lever for turning the said gear-wheel, means, substantially as described, for disengaging the said pawl from the said gear-wheel, and a releasing-arm held alongside the uppermost dog and adapted to be actuated by the said lever, substantially as shown and described.

15. In a saw-mill dog, the combination, with a standard and a vertical frame adjustable horizontally thereon, of a vertically-sliding carriage mounted on and carried by the frame, a dog secured thereto, a gear-wheel mounted on the said carriage and provided with an operating-lever having a pawl engaging said gear, a vertically-sliding rack on said frame and engaged by said gear, and a dog on the lower end of the rack, substantially as set forth.

20. The combination, with the frame, a vertically-sliding rack thereon provided with a dog, and a spring secured at its upper end to the frame and at its lower end to a projecting part at the lower end of the rack to support

the rack, of a vertically-sliding carriage on the frame provided with a dog and means for locking the said carriage to the rack to yield therewith, substantially as set forth.

35

25. The combination, with the frame having vertical guideways, a rack having a free up-and-down movement only in the frame between said guideways and carrying the lower dog, of an upper carriage mounted to slide vertically on said guideways in either direction and held thereby from lateral movement on said frame, an upper dog carried by said carriage, a gear also mounted on the carriage and meshing into the rack, and an operating-40 lever provided with a pawl engaging the said gear, whereby the rack and both dogs will be permitted to simultaneously yield vertically, substantially as set forth.

30. In a saw-mill dog, the combination, with a carriage and a dog secured thereon, of a gear-wheel mounted to turn in the said carriage, a lever fulcrumed on the shaft of the said gear-wheel and carrying a cam, and a releasing-arm pivoted on the said dog and extending in line with the latter, substantially as shown and described.
